C. L. PLUNKETT.

COUCH BED.

APPLICATION FILED DEO. 2, 1908.

Patented Feb. 21, 1911.

2 SHEETS-SHEET 1.

FIG. 1.

UNITED STATES PATENT OFFICE.

CHARLES L. PLUNKETT, OF NEW YORK, N. Y., ASSIGNOR TO AMERICAN COUCH COMPANY, OF BROOKLYN, NEW YORK, A CORPORATION OF NEW YORK.

COUCH-BED.

984,600.

Specification of Letters Patent.

Patented Feb. 21, 1911.

Application filed December 2, 1908. Serial No. 465,631.

To all whom it may concern:

Be it known that I, CHARLES L. PLUNKETT, a citizen of the United States, residing in New York, borough of Manhattan, in the county of New York and State of New York; have invented certain new and useful Improvements in Couch-Beds, of which the following is a specification.

This invention relates to couch beds, and more particularly to that class of couch beds in which one member making up the bed moves or slides with relation to the other to form either a double or a single bed or couch, the object of the present invention being to provide a couch bed with means for opening and closing a folding mattress, and which means will also simultaneously shift a storage receptacle into position to support such mattress when unfolded, whereby such receptacle may be utilized to support the mattress when opened to form a double bed.

A further object of the invention is the provision of an extremely simple and inexpensive means which will shift or slide one section of a pair of nesting couch-bed sections so as to form either a single or a double bed and which will also simultaneously swing open or close a folding mattress, and in addition will carry into or out of position for use a suitable storage receptacle, the parts being so organized, however, in several of the embodiments thereof, that the storage receptacle is readily accessible in any position of the shiftable section of the couch bed.

A further object is the provision of an improved couch bed made up of two sliding sections, one of which is carried or supported by a storage receptacle in such manner however, that its metallic fabric will move or slide between a side bar and the metallic fabric of the other section while the storage receptacle will move or slide below the side bar of such last section.

In the drawings accompanying and forming part of this specification, Figure 1 is an end view of this improved couch bed closed to form a couch; Fig. 2 is also an end view, with the shiftable section partly moved out and the folding mattress partly open; Fig. 3 is an end view of the bed sections opened to form a double bed, one form of the storage receptacle being shown partly in section; Fig. 4 is a perspective

view of this improved bed, with the book or folding mattress removed and showing only a part of the metallic fabrics in position, this view illustrating a somewhat different form of storage receptacle; Fig. 5 is an end view of the shiftable section of the bed, illustrating a somewhat different form of storage receptacle; Fig. 6 is an end view of the shiftable bed section, with parts thereof broken away and illustrating a somewhat different form of storage receptacle; and Fig. 7 is a detail view of a supporting bar for the metallic fabric of the shiftable section of the bed. Similar characters of reference indicate corresponding parts throughout the different figures of the drawings.

In those forms of couch beds in which one section shifts, moves or slides with relation to the other section, thereby to form either a double or a single bed, it is desirable to provide some means for the storage of the bed clothing during the day, or when the structure is transformed into a couch, and also to have such bed clothing readily accessible so that when the bed is formed into a double bed the bed clothing may be thrown upon the mattress, thus obviating the necessity of carrying the bed clothing to and storing the same in a cupboard during the day and again carrying it back to the bed at night. To obtain the greatest advantage from such a storage receptacle, however, it must be in such a position that access thereto can be readily had at a time when the bed clothing can be readily removed from the bed or placed thereon without the necessity of handling it twice.

In the present embodiment of this improved couch bed, the same is made up of two members or sections, one of which, for the present purposes, may be considered as the main or stationary section and the other the shiftable or extensible section, although, obviously, either section may be shifted relatively to the other. In the present instance that section which is shown as the shiftable section is made up of a storage receptacle and a metallic fabric, whereby it may be readily shifted away from or toward and under the main section, as occasion may require. The section 2 of the bed, which for the present purposes is designated the main or stationary section, preferably comprises a pair of end frames 3 and 4, each compris-

ing a horizontal bar 5 provided with a pair of legs or supports 6 usually provided with casters 7. These end frames are connected by a pair of side bars 8 and 9, a suitable stiffening strip 10 also being provided for securing the end frames together at one side thereof. Stretched between these end frames is a metallic fabric 11 attached thereto in any suitable manner. The section 12, which 10 in the present instance is designated as the shiftable section, likewise comprises a pair of end frames 13 and 14, each of which is provided with depending members 15 attached to the end of a suitable storage receptacle or box 16, whereby this section of the bed comprises the receptacle and the metallic fabric 17, which is stretched between the end frames, so that the storage receptacle in this instance takes the 15 place of the side bars and the stiffening means which connect the end frames of the main section. The storage receptacle 16 is of such height that it will readily pass under the side bar 9 of the main section of the bed 20 and may be provided with suitable casters 18 adapted to rest on the floor. The horizontal metallic supporting members, 13 and 14, of the end frames of this extensible section, however, are located above the side bar 30 9 and, in the present instance, below the metallic fabric 11 of the main section, so that the metallic fabric 17 of the extensible section slides between the side bar and the metallic fabric of the main section, while the 35 storage receptacle is located below both of said metallic fabrics.

The structure so far described makes up a very complete and desirable bed, as it provides a bed which can be easily transformed 40 into a double or a single bed or couch, while also furnishing, in connection therewith, a suitable storage receptacle which, in several of the forms shown herein, is readily accessible in either form of the 45 bed.

The mattress 19 is made as a folding or book mattress made of two parts 20 and 21 hinged or joined together along one edge, as at 22. For the purpose of shifting the storage receptacle 16 and also for opening and closing the folding or book mattress 19, suitable means is provided, which, in the present instance, comprises a swinging bar 23, preferably of U-shaped form, pivoted at its 50 ends, as at 24, to the end frames 3 and 4 of the main section 2, and in this instance at the inner ends of such end frames. This swinging bar is connected by a pair of links 25 to the storage receptacle and thereby to the extensible section of the bed, for which purpose a pair of brackets 26, to which the links 25 are pivoted, are attached to the inner ends of the end frames 13 and 14. The folding mattress 19, which rests upon 55 the metallic fabric 11 of the main section

when the bed is in the form of a couch, is made, as stated, in two parts, one part or half of which, as 20, is usually fastened to the top of the metallic fabric 11 of the main section, the other half, as 21 being secured 70 to the swinging bar 23 in any suitable way, as by being laced thereto at 27. When this swinging bar is shifted from the position shown in Fig. 1 to the position shown in Fig. 2, and from thence to the position shown 75 in Fig. 3, the mattress will be spread open so as to rest upon the top of both metallic fabrics, thereby forming a double bed. That half of the mattress, as 21, which rests upon the metallic fabric of the extensible section 80 is usually made somewhat thicker than the other half to compensate for the slightly lower position of the metallic fabric of this section relatively to the metallic fabric of the main section of the bed, although these 85 two fabrics are, because of the arrangement herein shown whereby the fabric of the extensible section slides between the metallic fabric and a side bar of the main section, nearly level. 90

While in the form of couch bed shown in Figs. 1 to 5 inclusive, access to the storage receptacle is entirely practicable whether the bed be open or closed, yet it is desirable that such access be permitted when the 95 folding mattress is partly open, so that, for instance, when the bed is to be transformed into a double bed the pillows, covers and other appurtenances of the bed can be taken from the storage receptacle and thrown on 100 to the ticking or inside of the book mattress, whereas if this could only be done when the bed is in the form of a couch these appurtenances must be thrown upon the top of the folded mattress when it is in the position 105 shown in Fig. 1 and then subsequently removed, or else thrown upon a chair and then again moved when the bed is opened and placed upon the inside of the folded mattress or upon the ticking, thus requiring 110 two handlings thereof. Consequently in all forms of the present improvement the organization is such that when the storage receptacle has been shifted out from under the main section a reasonable distance the 115 folded mattress is also partly opened, as shown in Figs. 2 and 4, so that the bed accessories when removed from the storage receptacle can be immediately placed inside of the folding mattress where they are to be spread, thus obviating the necessity of twice handling the pillows and other appurtenances. This is a great advantage, especially when heavy blankets and other coverings of weight must be handled by a 120 woman. 125

In the form of storage receptacle shown in Figs. 1 to 3 the front thereof is in the form of a hinged cover 30, this being hinged at its lower edge to the bottom of the re- 130

ceptacle, so that it may fall down and permit access to the box. To provide increased accessibility to the box, however, the front thereof may be formed in the manner shown in Fig. 4, in which the box is inclined at its front and an inclined cover 31 provided, which when thrown open affords access both downwardly and inwardly to the box, this not being interfered with by the metallic fabric of the extensible section by reason of the fact that the box is somewhat lower than the fabric, as shown in Fig. 4.

In the form shown in Fig. 5 the box is provided with a suitable drawer 32, which, when the storage receptacle is shifted outwardly, can in turn be pulled out to obtain access to the interior of the drawer.

In the form shown in Fig. 6, the metallic fabric of the extensible section is made in two parts, this being permitted by forming each end frame 13 and 14 as two members and hinging them together, as at 40, a suitable brace or bar 41 of drop formation having depending portions 42 adapted to rest upon the top of the box, connecting the two horizontal bars of the end frames together so as to prevent the metallic fabric from pulling them toward each other. The front portions of the outer or shiftable portion 30 may also be braced by a bar 42', illustrated by the dotted circle in Fig. 6. When the extensible section has been shifted outwardly into position shown in Fig. 6, at which time the folded mattress is partly open, the outer half of this extensible section can be thrown upward, as shown in said Fig. 6, and the lid 45 of the box raised, or as shown in said Fig. 6 the throwing upward of the extensible section also raises the lid 45 of the box, as 40 the lid is attached by some suitable means as a wire 46, to the extensible section, whereby access can be obtained to the box at the top thereof, thus obviating the necessity of providing it with a drawer as in Fig. 5. In 45 this form, however, access to the box is only possible when the extensible section is partly shifted outwardly to permit the outer half thereof to be swung upwardly, while in the other forms of the improvement the box 50 can be opened or closed even when the bed is closed to form a couch. So likewise the drawer 32 can be drawn out at any time.

The storage receptacle or box may be made of metal or of cedar, and when formed of the latter material, it constitutes a very efficient receptacle for the storage of furs or other articles during summer, as it is well known that cedar will prevent injury of articles stored therein by moths, and as 60 the receptacle is sufficiently large to enable it to be used not only as a place for storing bed clothing, but also for wearing apparel, it thus affords a very convenient storage means, especially as it is located, and in the main concealed, under the couch at all times,

bot' when the same is in the form of a couch or a double bed.

By means of the swinging bar 23, not only is the folding mattress opened and closed, but the storage receptacle, which constitutes the support for the mattress, is also simultaneously shifted in or out, according to the direction of movement of the swinging bar, and this can easily be done by a person standing at the end of the couch instead of in the middle of the front thereof. Moreover, in all forms of the improvement, the storage receptacle is readily accessible without the necessity of lifting one half of the entire folding mattress, for even in Fig. 6 it is not necessary to lift only a quarter of the whole mattress when down, and it can be lifted before the sectional or folding mattress is put down, and in the other forms of the improvement no lifting of the mattress or the frame which carries it is required.

It will thus be seen that in the present improvement the storage receptacle carries or constitutes the means of support for the folding mattress, that is to say, the end frames of the extensible section are secured directly to the storage receptacle and serve to support the folding mattress when the same is thrown over upon them.

I claim as my invention:

1. In a couch bed, the combination of a pair of bed sections, one shiftable relatively to the other and each carrying a yielding mattress support one resting flatwise over the other to form the seat when the structure is in the form of a couch, a storage receptacle forming a part of said shiftable section and located below the plane of said yielding mattress supports, a folding mattress for said sections, and means connected with said sections and with said folding mattress and adapted to simultaneously shift the shiftable section and storage receptacle and open or close said mattress.

2. In a couch bed, the combination of a pair of telescoping bed sections each having a yielding mattress supporting means connected thereto and one movable relatively to the other, the yielding mattress supporting means of one section lying flatwise over the other when the structure is in the form of a couch thereby to form the seat, a folding mattress therefor, a storage receptacle forming a part of one section and located below said yielding mattress supporting means when the sections are telescoped, and means attached to said folding mattress and operative to open or close the bed and fold or unfold the mattress, and also to shift the storage receptacle.

3. In a couch bed, the combination of a main and an extensible section, each comprising a pair of end frames having a metallic fabric carried thereby, the main sec-

4. In a couch bed, the combination of a main and an extensible section, each comprising a pair of end frames having a metallic fabric stretched therebetween, the main section having side bars connecting said end frames and the extensible section comprising a storage receptacle supporting its end frames, the metallic fabric of the extensible section sliding between a side bar and the metallic fabric of the main section, a folding mattress for said bed, and means for sliding one of said sections relatively to the other and simultaneously opening or closing said mattress. 70
5. In a couch bed, the combination of a main and an extensible section, each comprising a pair of end frames having a metallic fabric stretched therebetween, the main section having side bars connecting said end frames and the extensible section comprising a storage receptacle supporting its end frames, the metallic fabric of the extensible section sliding between a side bar and the metallic fabric of the main section, a folding mattress for said bed, and means for sliding one of said sections relatively to the other and simultaneously opening or closing said mattress. 75
6. In a couch bed, the combination of a main and an extensible section, each comprising a pair of end frames having a yielding mattress supporting means connected thereto, the main section having side bars connecting said end frames and the extensible section comprising a storage receptacle supporting its end frames, the yielding mattress supporting means of the extensible section sliding between a side bar and the yielding mattress supporting means of the main section, a folding mattress for said bed, and a swinging bar connected to said sections and swinging above the yielding mattress supporting means for sliding one of said sections relatively to the other and simultaneously opening or closing said mattress. 80
7. In a couch bed, the combination of a pair of bed sections, one shiftable relatively to the other and one comprising a storage receptacle and mattress supporting means connected one with the other and including cross bars thereabove, each of said sections having a metallic fabric carried thereby one lying flatwise over the other when the structure is in the form of a couch, a folding mattress for said bed, and means for folding and unfolding said mattress to spread the same on to the shiftable section when the structure is in the form of a double bed, said storage receptacle being movable with the shiftable section. 85
8. In a couch bed, the combination of a pair of bed sections, one shiftable relatively to the other and each comprising end frames having a metallic fabric stretched therebetween, the structure is in the form of a couch to form the seat thereof, one of said sections having its end frames of hinged formation intermediate its ends whereby a part of such frame may be swung upward, the metallic fabric of one section sliding between a side bar and the metallic fabric of the other section. 90
9. In a couch bed, the combination of a pair of bed sections, one shiftable relatively to the other and one comprising a storage receptacle carrying a mattress supporting means and the other also having mattress supporting means, a folding mattress for said bed, and means for folding and unfolding said mattress to spread the same on to said supporting means, the mattress supporting means carried by the storage receptacle comprising a fixed part and a hinged part, whereby access to the storage receptacle is permitted. 95
10. In a couch bed, the combination of a pair of bed sections, each comprising end frames and a metallic fabric stretched therebetween, a storage receptacle to which the end frames of one section are attached, the said end frames carried by the storage receptacle having a hinged portion whereby access to the storage receptacle is permitted. 100
11. In a couch bed, the combination of a pair of bed sections, each comprising end frames and a metallic fabric stretched therebetween, a storage receptacle to which the end frames of one section are attached, the said end frames carried by the storage receptacle having a hinged portion whereby access to the storage receptacle is permitted, a folding mattress for said bed, one part lying flatwise upon the other when the structure is in the form of a couch, and means for folding and unfolding said mattress to spread the same on said metallic fabrics. 105
12. In a couch bed, the combination of a pair of bed sections, one shiftable relatively to the other and each comprising end frames having a metallic fabric stretched therebetween, one lying flatwise over the other when the structure is in the form of a couch to form the seat thereof, one of said sections having its end frames of hinged formation intermediate its ends whereby a part of such frame may be swung upward, the metallic fabric of one section sliding between a side bar and the metallic fabric of the other section. 110
13. In a couch bed, the combination of a pair of bed sections, one shiftable relatively to the other and each comprising end frames having a metallic fabric stretched therebetween, one lying flatwise over the other when the structure is in the form of a couch to form the seat thereof, one of said sections having its end frames of hinged formation intermediate its ends whereby a part of such frame may be swung upward, the metallic fabric of one section sliding between a side bar and the metallic fabric of the other section. 115
14. In a couch bed, the combination of a pair of bed sections, one shiftable relatively to the other and each comprising end frames having a metallic fabric stretched therebetween, one lying flatwise over the other when the structure is in the form of a couch to form the seat thereof, one of said sections having its end frames of hinged formation intermediate its ends whereby a part of such frame may be swung upward, the metallic fabric of one section sliding between a side bar and the metallic fabric of the other section. 120
15. In a couch bed, the combination of a pair of bed sections, one shiftable relatively to the other and each comprising end frames having a metallic fabric stretched therebetween, one lying flatwise over the other when the structure is in the form of a couch to form the seat thereof, one of said sections having its end frames of hinged formation intermediate its ends whereby a part of such frame may be swung upward, the metallic fabric of one section sliding between a side bar and the metallic fabric of the other section. 125
16. In a couch bed, the combination of a pair of bed sections, one shiftable relatively to the other and each comprising end frames having a metallic fabric stretched therebetween, one lying flatwise over the other when the structure is in the form of a couch to form the seat thereof, one of said sections having its end frames of hinged formation intermediate its ends whereby a part of such frame may be swung upward, the metallic fabric of one section sliding between a side bar and the metallic fabric of the other section. 130

13. In a couch bed, the combination of a pair of bed sections, one shiftable relatively to the other and each comprising a pair of end frames having a metallic fabric stretched therebetween, the metallic fabric of one section sliding between the metallic fabric and a side bar of the other section, a storage receptacle carried by the shiftable section and movable under the side bar of the other section, the end frames of the shiftable section having a hinge formation, and said storage receptacle having a lid opened and closed on the shifting of the hinged portion of said shiftable section. 70
14. In a couch bed, the combination of a pair of bed sections one shiftable relatively to the other and each made up of a pair of end frames having a metallic fabric stretched therebetween, one of said sections having a part of its metallic fabric shiftable relatively to another part thereof, a storage receptacle located below said last section and having a shiftable cover, and a connection between said cover and the shiftable portion 75 of said fabric whereby on the shifting of said fabric the cover will be opened or closed. 80
15. In a couch bed, the combination of a pair of bed sections one shiftable relatively to the other and each made up of a pair of end frames having a metallic fabric stretched therebetween, one of said sections having a part of its metallic fabric shiftable relatively to another part thereof, a storage receptacle located below said last section and having a shiftable lid, a connection between said lid and the shiftable portion of said fabric whereby on the shifting of said fabric the lid will be opened or closed, a sectional mattress for said sections, and means connecting said sections with said mattress and adapted to simultaneously shift the shiftable section and open or close said mattress. 85
16. In a couch bed, the combination of a pair of bed sections one shiftable relatively to the other and each comprising a pair of end frames having a metallic fabric stretched therebetween, the metallic fabric of one section sliding between the metallic fabric and a side bar of the other section, a storage receptacle carried by the shiftable section and movable under the side bar of the other section, said shiftable section having a part of its metallic fabric hinged for raising and lowering it, and said storage receptacle having a lid connected to the hinged part of said metallic fabric and opened or closed on the shifting of said hinged part of the shiftable section. 90
17. In a couch bed, the combination of a pair of bed sections one shiftable relatively to the other and each comprising a pair of end frames having a metallic fabric stretched therebetween, the metallic fabric 95
- of one section sliding between the metallic fabric and a side bar of the other section, a storage receptacle carried by the shiftable section and movable under the side bar of the other section, said shiftable section having a part of its metallic fabric hinged for raising and lowering it and said storage receptacle having a lid connected to the hinged part of said metallic fabric and opened or closed on the shifting of said hinged part of the shiftable section. 100
18. In a couch bed, the combination of a pair of bed sections one shiftable relatively to the other and carrying a storage receptacle having a shiftable lid, each of said sections carrying a yielding mattress supporting means, the yielding mattress supporting means of the shiftable section being connected to permit it to be raised and lowered at its front portion, and means connecting the shiftable lid with the shiftable yielding mattress supporting means whereby on raising or lowering the latter the lid will be shifted. 105
19. In a couch bed, the combination of a pair of bed sections one shiftable relatively to the other and carrying a storage receptacle having a shiftable lid, each of said sections carrying a yielding mattress supporting means, the yielding mattress supporting means of the shiftable section being connected to permit it to be raised and lowered at its front portion, means connecting the shiftable lid with the shiftable yielding mattress supporting means whereby on raising or lowering the latter the lid will be shifted, a sectional mattress for said bed sections, and means connecting said mattress with said sections thereby to simultaneously open or close the mattress and shift the shiftable bed section. 110
20. In a couch bed, the combination of a bed section comprising a pair of connected end frames, yielding mattress supporting means fixedly secured thereto one part thereof of shiftable relatively to another part and above the top of said end frames and independently of any movement of said end frames, a storage receptacle carried by said bed section and having a shiftable cover, and a connection between said cover and the shiftable portion of the yielding mattress supporting means whereby on shifting the latter the cover will be opened or closed. 115
